UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

OVERSEAMING MECHANISM FOR SEWING-MACHINES.

1,293,560.

Specification of Letters Patent.

Patented Feb. 4, 1919.

Application filed December 27, 1915. Serial No. 68,788.

To all whom it may concern:

Be it known that I, DUDLEY S. SEYMOUR, a citizen of the United States, residing at Oak Park, in the county of Cook, State of Illinois, have invented certain new and useful Improvements in Overseaming Mechanism for Sewing-Machines, of which the following is a description, reference being had to the accompanying drawing and to the figures of reference marked thereon.

The invention relates to new and useful improvements in overseaming mechanism for sewing machines and more particularly to the mechanisms for operating the looper and spreader.

An object of the invention is to provide a sewing machine of the above character with mechanisms for operating the looper and spreader wherein a greater portion of the operating parts are housed within the standard of the sewing machine.

A further object of the invention is to provide a machine of the above character with mechanism for operating the looper wherein said looper may be given a dwell at the forward end of its stroke and wherein the actuating shaft for the looper extends transversely of the standard and is connected to said looper from the rear side of said standard.

These and other objects will in part be obvious and will in part be hereinafter more fully disclosed.

In the drawings, which show by way of illustration one embodiment of the invention:—

Figure 1 is a view partly in front elevation and partly in section of a sewing machine having the improvements embodied therein;

Fig. 2 is a view partly in plan and partly in section showing the looper operating mechanism, the spreader operating mechanism and the feeding mechanism;

Fig. 3 is a view partly in end elevation and partly in section with certain of the parts omitted and showing more particularly the manner of mounting the spreader and also the manner of mounting the looper;

Fig. 4 is a view partly in front elevation and partly in section showing the

needle, the looper and the spreader and a portion of the operating mechanisms therefor;

Fig. 5 is an enlarged view showing the relation of the needle, the looper and the spreader to the fabric just as the spreader is engaging the looper thread;

Fig. 6 is a similar view but showing the spreader as having moved slightly forward to form the loop in the looper thread;

Fig. 7 is a similar view but showing the spreader having positioned the looper thread loop for the needle to enter;

Fig. 8 is a similar view but showing the spreader and looper fully retracted;

Fig. 9 is a top plan view of a fabric stitched on my improved machine; and

Fig. 10 is a bottom plan view of the same.

The invention is shown as embodied in a sewing machine having a supporting bed 1 carrying a hollow standard 2 having an overhanging arm 3. At the forward end of the overhanging arm is a needle supporting head 4. The needle bar 5 reciprocates in this supporting head and carries a needle 6. Said needle bar is reciprocated by a needle lever 7 pivoted at 8 to the overhanging arm and connected by a link 9 to the needle bar. Said needle lever 7 is oscillated by a link 10 which coöperates with an eccentric on the main shaft 11 of the machine. The material to be stitched is carried by a work support 12. A presser foot 13 holds the material on the work support and a feed dog 14 advances the material over the work support. Said feed dog is carried by a feed bar 15 which is raised and lowered by a suitable cam or eccentric on the main shaft 11 and this feed bar is moved back and forth by an eccentric strap 16 which is connected to the feed rocker at the rear side of the machine. The feed bar 15 is also pivoted to said feed rocker. These parts are of the usual construction and will not need further description.

Coöperating with the needle beneath the work support is a thread carrying looper 18. Said thread carrying looper is fixed to the forward end of a rock shaft 19 mounted in suitable bearings 20 and 21 carried by the supporting bed of the machine. This

rock shaft has an arm 22 secured to its rear end which projects upwardly therefrom. A link 23 is secured to a ball stud carried by this upwardly projecting arm 22. The 5 other end of this link is connected to a ball stud carried by an arm 24 fixed by a screw 25 to a cross shaft 26.

The standard 2 as above noted is hollow and has an inwardly projecting boss 27 10 which forms a bearing for the cross shaft 26. Said cross shaft 26 at its inner end and within the hollow standard is provided with an arm 28 which is secured to the cross shaft by a screw 29. This arm 28 is carried by a link 30 with the needle lever extension 31.

As the needle lever extension oscillates it will impart an oscillation to the shaft 26 and this will move the link 24 back and forth and thus rock the looper.

20 The looper is mounted so as to coöperate with the needle wholly beneath the work support. Said looper moves forward into the needle loop.

The link 30 connecting the needle lever extension to the arm 28 is substantially in alignment with the needle lever extension when the looper is at the forward end of its stroke and, therefore, said looper is given a dwell at this time. Coöoperating with the

30 looper and with the needle is a spreader 32. This spreader 32 is mounted in an elbow lever 33 which is pivoted at 34 to a bracket 35. Said bracket 35 is fixed to the bed plate by suitable clamping bolts. The elbow lever

35 33 has a rearwardly projecting arm 36. A link 37 is connected to the outer end of this arm and said link is also connected to an arm 37 which is pivoted at 38 to the bracket 35.

A link 39 is connected to the pivoted 40 bolt 40 which joins the link 36 and the arm 37. This link 39 at its other end is pivoted to a ball stud carried at the lower end of a lever 42 which is pivoted at 43 on a stud carried by a bearing mounted within the

45 hollow standard. The other arm of the lever is connected by an eccentric strap 44 and this eccentric strap coöperates with an eccentric on the main shaft 11.

The spreader is provided with a forked 50 end 45 and also with a spreading finger 46. This spreading finger is disposed in rear of the needle, and the needle on its downward stroke holds its own thread over the spreading finger and this prevents the previously

55 locked loops from becoming slack and assists in the formation of the stitches. The spreader *per se* and the mechanism for operating the same form no part of the present invention except in connection with the other

60 elements of the sewing machine. Said spreader mechanism and said spreader are shown, described and claimed in my copending application, Serial No. 68,787, filed of even date herewith.

65 When the spreader is at the lower end of

its stroke the link 36 and the arm 37 are substantially in alignment and this will give a dwell to the spreader at this time.

As clearly shown in Fig. 5 the spreader when at the lower end of its stroke is just 70 below the path of movement of the looper. The looper in this figure has reached the forward end of its stroke and is at a dwell, by reason of the fact that the link 30 and the needle lever extension 31 are at this time 75 substantially in alignment. This dwell to the looper gives ample time for the spreader to move forward so as to engage the looper thread.

In Fig. 6 of the drawing I have shown 80 the spreader forming the looper thread into a loop. Said spreader when it engages the looper thread is moved substantially in a vertical direction for the reason that the pivotal support of the spreader is substantially 85 on a horizontal line passing through the forward end of the spreader. When the spreader reaches the upper end of its stroke it is moving in a substantially horizontal path for the reason that the pivotal point 90 of the spreader is close to the needle beneath the work support. The spreader positions the looper thread loop for the needle to enter as shown in Fig. 7. The looper during this time has remained substantially 95 at the forward end of its stroke. After the needle has entered the looper thread loop then the looper and spreader are both retracted to the position shown in Fig. 8 and the continued downward movement of the 100 needle draws up on the loops and sets the stitch.

It will be noted from the above that the greater portion of the operating mechanism for the spreader and for the looper is housed 105 within the hollow standard. My machine is particularly adapted for operating upon heavy material such as coarse burlap for forming bags and it is desirable in this type of machine to inclose and house as far as 110 possible the operating parts so as to keep the lint and dirt away from the operating parts. Furthermore, by my improved mechanism the looper is operated from a cross shaft extended transversely of the hollow 115 standard and the connection to this cross shaft is in rear of the standard. The operating mechanism for the looper, therefore, is entirely free from the operating mechanism for the spreader and gives greater 120 room and freedom of movement for the operating parts. This positioning of the looper operating shaft in an extended boss formed in the hollow standard also makes a very durable support for the operating 125 mechanism for the looper.

In Figs. 9 and 10 I have shown a fabric indicated at F, the needle thread is indicated at n while the looper thread is indicated at l. It will be noted that the needle 130

thread loops pass through the fabric, a looper thread loop passes through the needle loop around the edge of the fabric and is locked by the next needle thread loop as it passes through the fabric.

Having thus described my invention what I claim as new and desire to secure by Letters Patent, is:—

1. A sewing machine comprising in combination, a work support, a hollow standard carrying an overhanging arm, a needle reciprocating at the free end of said overhanging arm, a needle lever for reciprocating said needle, a looper coöperating with the needle beneath the work support, a cross shaft mounted in a suitable bearing in said standard, an arm carried by said cross shaft and located in rear of the standard, a link actuated by said arm for oscillating said looper, a second arm carried by said cross shaft and located within said hollow standard, a link connecting said second arm with an extension on the needle lever, said link and said needle lever extension being so positioned as to move substantially into alinement when the looper is at the forward end of its stroke for giving a dwell thereto.

2. A sewing machine comprising in combination, a work support, a hollow standard carrying an overhanging arm, a needle reciprocating at the free end of said overhanging arm, a needle lever for reciprocating said needle, a looper coöperating with the needle beneath the work support, a cross shaft mounted in a suitable bearing in said standard, an arm carried by said cross shaft and located in rear of the standard, a link actuated by said arm for oscillating said looper, a second arm carried by said cross shaft and located within said hollow standard, a link connecting said second arm with an extension on the needle lever, said link and said needle lever extension being so positioned as to move substantially into alinement when the looper is at the forward end of its stroke for giving a dwell thereto, a spreader coöperating with the looper beneath the work support and with the needle above the work support and means for oscillating said spreader.

3. A sewing machine comprising in combination, a work support, a hollow standard carrying an overhanging arm, a needle reciprocating at the free end of said overhanging arm, a needle lever for reciprocating said needle, a looper coöperating with the needle beneath the work support, a cross shaft mounted in a suitable bearing in said standard, an arm carried by said cross shaft and located in rear of the standard, a link actuated by said arm for oscillating said looper, a second arm carried by said cross shaft and located within said hollow standard, a link connecting said second arm with an extension on the needle lever, said link and said needle

lever extension being so positioned as to move substantially into alinement when the looper is at the forward end of its stroke for giving a dwell thereto, a spreader coöperating with the looper beneath the work support and with the needle above the work support, means for oscillating said spreader, a spreader coöperating with the looper beneath the plane of the work support and with the needle above the work support, means for oscillating said spreader and for giving a dwell thereto at the lower end of its stroke.

4. A sewing machine comprising in combination, a hollow standard, an overhanging arm carried thereby, a needle bar carrying said needle and reciprocating in said overhanging arm, a needle lever for reciprocating the needle, said needle lever having an extension extending into said hollow standard, a work support, a lever coöperating with the needle beneath the work support, a cross shaft mounted in a suitable bearing in one wall of the hollow standard, means located within the hollow standard for connecting said cross shaft to the needle lever extension and means for oscillating the looper from the outer end of said cross shaft, a spreader coöperating with the looper beneath the plane of the work support and with the needle above the work support, a rock lever mounted in said hollow standard, means within said hollow standard for actuating the rock lever and devices for connecting the said rock lever with said spreader for oscillating the same.

5. A sewing machine comprising in combination, a hollow standard, an overhanging arm carried thereby, a needle bar carrying said needle and reciprocating in said overhanging arm, a needle lever for reciprocating the needle, said needle lever having an extension extending into said hollow standard, a work support, a lever coöperating with the needle beneath the work support, a cross shaft mounted in a suitable bearing in one wall of the hollow standard, means located within the hollow standard for connecting said cross shaft to the needle lever extension and means for oscillating the looper from the outer end of said cross shaft, a spreader coöperating with the looper beneath the plane of the work support and with the needle above the work support, a rock lever mounted in said hollow standard, means within said hollow standard for actuating the rock lever and devices for connecting the said rock lever with said spreader for oscillating the same, said devices for oscillating the spreader including toggle links movable substantially into alinement when the spreader is at the rear end of its stroke.

6. A sewing machine comprising in combination, a hollow standard, an overhanging

arm carried thereby, a needle bar carrying said needle and reciprocating in said overhanging arm, a needle lever for reciprocating the needle, said needle lever having an extension extending into said hollow standard, a work support, a lever coöperating with the needle beneath the work support, a cross shaft mounted in a suitable bearing in one wall of the hollow standard, means located within the hollow standard for connecting said cross shaft to the needle lever extension and means for oscillating the looper from the outer end of said cross shaft, a spreader coöperating with the looper beneath the plane of the work support and with the needle above the work support, a rock lever mounted in said hollow standard, means within said hollow standard

for actuating the rock lever and devices for connecting the said rock lever with said spreader for oscillating the same, said devices for oscillating the spreader including toggle links movable substantially into alignment when the spreader is at the rear end of its stroke, said means for oscillating the cross shaft from the needle lever extension including a link movable substantially into alignment with the needle lever extension when the looper is at the forward end of its stroke for giving a dwell thereto.

In testimony whereof, I affix my signature, in the presence of two witnesses.

DUDLEY S. SEYMOUR.
